DESIGN FOR A MOUNTING BRACKET FOR AUTOMOBILE REARVIEW MIRROR

Glen A. Johnson, Connersville, Ind.

Application March 17, 1948, Serial No. 145,176

Term of patent 3½ years

(Cl. D14—6)

To all whom it may concern:

Be it known that I, Glen A. Johnson, a citizen of the United States, residing at Connersville, in the county of Fayette and State of Indiana, have invented a new, original, and ornamental Design for Mounting Bracket for Automobile Rearview Mirror, of which the following is a specification, reference being had to the accompanying drawing forming a part thereof.

Fig. 1 is a perspective view of a mounting bracket for automobile rearview mirror, showing my new design;

Fig. 2 is a side elevational view thereof;
Fig. 3 is a top plan view thereof; and

Fig. 4 is a front elevational view thereof.

I claim:

The ornamental design for a mounting bracket for automobile rearview mirror, as shown.

GLEN A. JOHNSON.
